UNITED STATES PATENT OFFICE.

ROBERT W. SCOTT, OF BABYLON, NEW YORK, ASSIGNOR TO SCOTT AND WILLIAMS, INC., OF NEW YORK, N. Y., A CORPORATION OF MASSACHUSETTS.

KNITTING NEEDLE.

Application filed December 30, 1922. Serial No. 609,850.

To all whom it may concern:

Be it known that I, ROBERT W. SCOTT, a citizen of the United States, residing at Babylon, in the county of Suffolk and State 5 of New York, have invented new and useful Improvements in Knitting Needles.

My invention is in the nature of an improvement on the two part or sliding latch knitting needle which forms the subject of 10 Patent No. 1,483,009 dated February 5, 1924, by A. E. Page. The object of my present invention is to so construct the needle as to prevent missing of stitches, especially in the taking of the loop by the casting or 15 transfer implement.

In the accompanying drawings:

Figure 1 is a perspective view of my improved needle.

Fig. 2 is a side elevation.

20 Figs. 3 and 4 are transverse sections taken at the lines 3—3 and 4—4 respectively, Fig. 2.

As in the Page patent above referred to, the needle comprises two parts in sliding 25 relation to each other, one being the loop-drawing part A with a hook *a* at its operative end, while the other part B is the casting or transfer implement, which is provided with a return bend hook *b*, and it may also 30 be provided with a forwardly projecting point *b'* if desired.

The body A' of the instrument A which is provided with a butt 7 to be acted on by suitable cams, is made relatively deep 35 and has on one side of its rear portion an open groove 5 to receive and guide a thinned tail piece 6 on the back end of the instrument B. This instrument B also has a butt 8, which is to be acted on by suitable cams 40 to reciprocate the instrument, these two instruments being guided together for their longitudinal motion in grooves in the knitting machine dial or cylinder, as the case may be.

45 In the construction of needle of the Page patent above mentioned, the side walls of

the grooves in the dial or cylinder were depended on to keep the two instruments A and B in the same plane, but in practice it has been found that this construction will 50 not keep that nice alignment of the operating ends of the instruments which is necessary to ensure the point *b* taking the old loop at all times correctly from the shank of the part A.

55 According to my invention, I provide on the adjacent edges of the shanks of the two instruments forward of said above mentioned tail piece a longitudinal tongue and groove sliding connection, consisting preferably of a tongue 9 on the edge of the instrument B, working in a longitudinal groove 10 in the adjacent edge of the shank of the instrument A, this groove 10 serving also to receive the point *b* of the instrument 60 B, when the latter is retracted, as shown in Fig. 2. At the same time the tail piece 6 guided in the side groove 5 will aid in otherwise keeping the two instruments in proper 65 relation, especially preventing tilting of the 70 instrument B.

I claim as my invention:—

1. A two-part knitting machine needle, one part having an open side groove in its rear portion to receive and guide a tail piece 75 on the other, the adjacent edges of the shanks of the two parts forward of said tail piece having a guiding groove connection.

2. A two-part knitting machine needle, one part having an open side groove in its 80 rear portion to receive and guide a tail piece on the other part, while the edge of the shank of one part forward of said tail piece has a longitudinal tongue and the adjacent edge of the shank of the other part has a 85 groove to receive said tongue, said groove being adapted also to receive a loop-taking hook on the tongued part, when the latter is retracted, as and for the purpose set forth.

In testimony whereof I have signed my 90 name to this specification.

ROBERT W. SCOTT.
